UNITED STATES PATENT OFFICE.

REMSSEN APPLEBY, OF NEW YORK, N. Y.

CIGAR-MOLD.

SPECIFICATION forming part of Letters Patent No. 292,398, dated January 22, 1884.

Application filed March 10, 1883. (No model.)

To all whom it may concern:

Be it known that I, REMSEN APPLEBY, of the city, county, and State of New York, have invented a new and useful Improvement in Cigar-Molds, of which the following is a full, clear, and exact description.

Reference is to be had to the accompanying drawings, forming part of this specification, in which similar letters of reference indicate corresponding parts in all the figures.

Figure 1 is a perspective view of the lower part of a set of cigar-molds illustrating my improvement. Fig. 2 is a perspective view of a portion of the upper part of the mold inverted. Fig. 3 is a front elevation of a part of the mold. Fig. 4 is a sectional elevation of the mold, taken through the line $x x$, Fig. 3; and Fig. 5 is an elevation of the inner side of a pair of tips.

20 The object of the invention is to construct the tips with points and flanges, so that they may be rigidly secured to the molds, as hereinafter described.

A represents the lower parts of the molds, which are attached to a board, B.

C are the upper parts of the molds, which are attached to a board, D. The parts C of the molds are centered upon the parts A by dowel or guide pins E, attached to the board 30 B, and which enter holes in the board D.

F are tips, made of metal or other suitable material, and which are recessed to give the proper shape to the heads of the cigars. The tips F are made with sharp edges around the recesses, which meet when the two parts of a mold are pressed together, so as to cut off the surplus tobacco, and thus prevent the tobacco in the heads of the cigars from being packed too closely.

40 The forward ends, G, of the ordinary molds

are cut away, as shown at H in Figs. 1, 2, and 4, to receive the tips F, which have points I upon the side parts of their inner ends, as shown in Fig. 5, to enter the forward ends of the molds A C, as shown in Fig. 4, and thus 45 keep the said tips in place.

Upon the outer ends of the tips F are formed rearwardly-projecting flanges J, which fit against the edges of the boards B D, and have inwardly-projecting points or edges upon their 50 ends to enter the said boards, and thus aid in keeping the tips F in place. The tips F are secured in place by screws, which pass through holes in the flanges J and enter the edges of the boards B D.

If desired, the tips F may be attached only to the upper molds, C, in which case the upper parts of the forward ends of the lower molds, A, are cut away, forming shoulders K, as shown in Fig. 1, against which the edges of 60 the tips F of the upper molds, C, strike to cut off the surplus tobacco, and which allow the cut-off parts or clippings to escape freely.

In my Patent No. 161,651 the cutting-edges pass each other; but I find this objectionable, 65 because it causes the point of the cigar to be packed and to draw badly. In order to avoid this, I make the edges to meet, thus still cutting off the surplus tobacco without packing the cigar-point, and at the same time enabling 70 me to secure the tips, so that they will not move and will do more accurate work.

What I claim as new is—

The tips F, made with points I and flanges J, whereby they may be rigidly secured to the 75 molds, as and for the purpose specified.

REMSSEN APPLEBY.
